[57] CLAIM

The ornamental design for a combined audible alarm and flashlight, as shown and described.

DESCRIPTION

FIG. 1 is a top, side, and end perspective view of a combined audible alarm and flashlight showing my new design;

FIG. 2 is a side elevational view, thereof the opposite side being a mirror image;

FIG. 3 is a top plan view thereof;

FIG. 4 is a bottom plan view thereof;

FIG. 5 is an end elevational view thereof;
FIG. 6 is the opposite end elevational view thereof; and
FIG. 7 is a top, opposite side and end perspective view thereof.

The fluorescent lamp bases are shown in broken lines in FIGS. 1 and 5 for illustrative purposes only.

FIG. 1

FIG. 2

FIG. 3

FIG. 4

FIG. 5

FIG. 6

FIG. 7
